UNITED STATES PATENT OFFICE.

GEORGE HENRY RICHARDSON, OF SAN FRANCISCO, CALIFORNIA.

COMBINATION NOTE-BOOK, COPY-HOLDER, AND TOOL-KIT.

No. 839,643.

Specification of Letters Patent.

Patented Dec. 25, 1906.

Application filed March 27, 1906. Serial No. 308,350.

To all whom it may concern:

Be it known that I, GEORGE HENRY RICHARDSON, a citizen of the United States, and a resident of San Francisco, in the county of 5 San Francisco and State of California, have invented a new and Improved Combination Note-Book, Copy-Holder, and Tool-Kit, of which the following is a full, clear, and exact description.

10 The invention relates to stationery; and its object is to provide a new and improved note-book stand, copy-holder, and tool-kit more especially designed for the use of stenographers and arranged to hold a note-book 15 or a loose copy in a most advantageous position, readily to accommodate various tools and to allow of convenient folding into comparatively little space for storing or for shipping purposes.

20 The invention consists of novel features and parts and combinations of the same, which will be more fully described herein-after and then pointed out in the claims.

25 A practical embodiment of the invention is represented in the accompanying drawings, forming a part of this specification, in which similar characters of reference indicate corresponding parts in all the views.

30 Figure 1 is a perspective view of the improvement. Fig. 2 is a side elevation of the same, showing the easel-frame folded and the note-book in position. Fig. 3 is a similar view of the same, showing the extension-frame of the easel-frame in an extended position to allow convenient access to the tools held on the base of the device or to allow said frame to be raised entirely over the note-book and set upright in place. Fig. 4 is a 35 like view of the same, showing the easel-frame locked in a raised position. Fig. 5 is a side elevation of the same, showing the easel-frame unlocked and supported on the note-book by the marker-bar. Fig. 6 is a like view of the improvement, showing the 40 easel-frame locked in a raised position and a loose copy held in place by the copy-clasp. Fig. 7 is a similar view of the same arranged for holding rolled-up copy in position at the top by the use of the marker-bar. Fig. 8 is a front elevation of the improvement. Fig. 45 9 is an enlarged transverse section of the same on the line 9 9 of Fig. 7. Fig. 10 is an enlarged side elevation of the front end por-

tion of the improvement, parts being in section; and Fig. 11 is a side elevation of the 55 upper portion of the easel-frame, its extension-frame, and end marker-bar.

A suitably-constructed base A is provided at its front end with a ridge B, preferably in the form of an easel-shelf, and on the rear 60 end of the said base A is formed integrally a ridge C.

A note-book D, opened up in V-shape, as illustrated in Figs. 1, 2, 3, 4, and 5, may be engaged with the ridges B and C, so as to 65 hold the note-book in position for the stenographer or type-writer readily to read the notes on the front page of the note-book. The rear pages of the note-book D are locked to the cover in the usual manner by a suitable rubber band E or the like, and a similar band may be used for holding the other leaves on the front cover of the note-book D. 70

By reference to the drawings it will be seen that by the arrangement described the note-book D is held in an extended position either between the back of the ridge B and the front of the ridge C or in between the ridges B and C, as indicated in Fig. 5. 75

On the base A, immediately in the rear of 80 the front ridge B, is hinged an easel-frame F, pressed on by a torsion-spring G normally to hold the easel-frame F in a closed or a folded position, as illustrated in Figs. 2 and 3, and the said easel-frame F is adapted to be 85 locked in a raised position by locking-bolts H, mounted to slide in suitable bearings arranged on the back of the ridge B. The said bearings of the easel-frame F are engaged by slides I' of an extension-frame I, provided 90 with an overhanging marker-bar I², adapted to extend on the face of the front leaf of the note-book D to indicate the line to be copied at the time, the said extension-frame I being shifted by the operator in a downward direction, so as to bring the marker-bar I² successively opposite the successive lines to be 95 copied from the front page of the note-book D. Now by having the spring G pressing the easel-frame F in a rearward direction it is 100 evident that the marker-bar I² rests firmly on the front page of the note-book D in case the bolts H are withdrawn. (See Figs. 1 and 5.) Loose leaves of copy may also be held 105 firmly, if desired, between the note-book D and the easel-frame F, pressing in its rear-

ward direction. If, however, it is desirable to remove the note-book D altogether, the easel-frame F may be used alone to support loose leaves of copy by drawing either or 5 both of the bolts H, thus holding the easel frame F and its extension-frame I locked in a raised position, as indicated in Figs. 4, 6, 7, and 8. In such case the loose leaves of copy 10 may rest against the upright easel-frame and when necessary may be held more securely at the top by a cross-bar I³, which may either be rigid or hinged, and when hinged to be adjusted by a thumb-screw I⁵. (See Figs. 1 and 8.)

15 A note-book with paper covers may be supported on the easel-frame F by sliding the extension-frame I down to the base A, placing the note-book through the easel-frame F as far as the center binding, and then sliding the 20 extension-frame I up again until the book binds against the cross-bar I⁴. To support loose copy that is larger than ordinarily on the easel-frame F, the extension-frame I is slid toward the top of the easel-frame F.

25 In order the better to hold loose copies at the lower edge in position on the easel-frame F, a copy-clasp J is provided and arranged in the front ridge B, the said copy-clasp J being provided with a handle J', extending under 30 an opening B', formed in the front member of the ridge B, as plainly indicated in Fig. 10. The copy-clasp J operates in conjunction with the rear member B² of the front ridge B, and the said clasp is pressed on by a torsion spring J² to clasp firmly the loose leaves between the copy-clasp J and the rear member 35 B² of the front ridge B.

When the device is not in use, the extension-frame I is closed in, and the easel-frame 40 F extends horizontally and rests with its cross-bar I³ in the rear ridge C.

On the upper surface of the base A, between the ridges B and C, is arranged a rack 45 for holding penholders, lead-pencils, a rubber eraser, an "erasing-shield," and an envelope-opener or paper-cutter, and this rack is preferably formed of two transversely-extending rack-bars K, each provided with corrugations K' and spring-tongues K² K³ at the ends 50 thereof, as plainly indicated in Fig. 9. Bolts K⁴ engage the rack-bars K and extend through elongated slots A', formed in the base A, to allow of giving the desired tension to the corrugations K' of the rack-bars by 55 shifting the bolts K⁴ after loosening the same in the base A. By reference to Fig. 9 it will be seen that the bolts K⁴ engage the rack-bars K between the inner ends of the tongues K² K³ and the beginning of the corrugations K'. In case the resiliency of the corrugations K' diminishes it is only necessary for the operator to loosen the bolts K⁴ and shift the same inwardly to give renewed tension 60 to the corrugations on the base A. On the

base A is also fastened in a suitable manner 65 a calendar L.

By reference to Fig. 2 it will be seen that when the easel-frame F is in a folded position the marker-bar I², as well as the cross-bar I³ of the extension-frame I, extends over the 70 tools to hold them securely in place when shipping or storing the device; but in case it is desired to use the tools it is only necessary to move the extension-frame outwardly (see Fig. 3) to disengage the marker-bar I² and 75 the cross-bar I³ from the said tools.

Having thus described my invention, I claim as new and desire to secure by Letters Patent—

1. A device of the class described, comprising a base having lengthwise-extending parallel ridges at the front and rear for supporting a note-book in an open display position, an easel-frame hinged on the front ridge and having a movable marking-bar, and a locking device on the said front ridge for locking the said frame in a raised position. 80

2. A device of the class described, comprising a base provided at the front with an easel-shelf, an easel-frame hinged on the base 90 in the rear of the easel-shelf, and a locking-bolt on the said shelf, adapted to engage the said frame to lock it in a raised position.

3. A device of the class described, comprising a base provided at the front with an 95 easel-shelf, an easel-frame hinged on the base in the rear of the easel-shelf, a locking-bolt on the said shelf, adapted to engage the said frame to lock it in a raised position, and an extension-frame slidable on the said easel- 100 frame, having an integral marking-bar.

4. A device of the class described, comprising a base provided at the front with an easel-shelf, an easel-frame hinged on the base in the rear of the easel-shelf, a locking-bolt 105 on the said shelf, adapted to engage the said frame to lock it in a raised position, and an extension-frame comprising upper and lower cross-bars slidable on the said easel-frame, and having an integral marking-bar, 110 the upper cross-bar of said slidable extension-frame being hinged.

5. A device of the class described provided with a base, a rack having corrugations and spring-tongues at the ends, for receiving articles, bolts for connecting the rack to the said base and an easel-frame hinged to the base, and foldable upon the rack, for retaining the articles on the rack in position. 115

6. A device of the class described, provided with a base having elongated slots, a rack having corrugations and spring-tongues at the ends for receiving articles, bolts for connecting the rack to the said base, said bolts 120 engaging the racks between the inner ends of the spring-tongues, and the outermost corrugations, and extending through the elongated slots in the said base, and an easel-frame 125

hinged to the base and foldable upon the rack, whereby to retain the articles on the rack in position.

7. A device of the class described, provided with a base having integral V-shape ridges at the front and rear ends, and a trough adjacent thereto.

8. A device of the class described, provided with a base having integral V-shape ridges at the front and rear ends, and a trough adja-

cent thereto, and a frame pivoted on the base in the rear of the front ridge, adapted to rest in the rear ridge.

In testimony whereof I have signed my name to this specification in the presence of ¹⁵ two subscribing witnesses.

GEOERGE HENRY RICHARDSON.
